SIGN

Benjamin Phillips, Cincinnati, Ohio, assignor to
The Phillips Pump & Tank Company, a corporation of Ohio

Application March 2, 1936, Serial No. 66,549

3 Claims. (Cl. 40—64)

This invention relates to signs, and is particularly directed to a type of sign which includes a frame including protective glass panes for displaying advertising cards, price cards, etc. It is the object of the present invention to provide a sign of this character in which the frame is readily formed in one part; which mounts the display card in a position where the rain or snow can not reach the same; which incorporates a conveniently operable means at the base thereof for holding the glass panes in position; and which includes a card retaining means independently removable relative to the pane retaining means, whereby a card can be readily inserted relative to the panes.

It is a further object to provide a sign of this character which can be read from either side, and in which proper ventilation is afforded for permitting the atmospheric conditions of the environment to exist within the card chamber between the spaced glass panes.

Other objects and further advantages will be more fully apparent from a description of the accompanying drawing, in which:

25 Figure 1 is a side view of the improved sign, showing portions thereof broken away for more fully illustrating the details of construction.

Figure 2 is a sectional view taken on line 2—2, Fig. 1, detailing the assembly of parts within the frame.

30 Figure 3 is a bottom plan view of the sign with a portion of the frame broken away for illustrating the glass and card retaining means with the card retaining means in an intermediate position of removal.

Figure 4 is a sectional view taken on line 4—4, Fig. 1, detailing the mounting of the glass panes or panels and showing the chamber for the card.

40 Figure 5 is a fragmentary sectional view taken on line 5—5, Fig. 4, further detailing the structure at the base edge of the sign.

Figure 6 is a perspective view of the card retaining slide, showing it in its normal or sprung condition as removed.

45 Referring to the drawing, the improved sign is shown as fixed against a vertical wall. Of course it will be appreciated that it can be placed on a horizontal surface as well. The frame element 10 of the sign includes attachment lugs 11 which are arranged in the form of oppositely extending feet 12 extending laterally at each side of the sign.

50 Glass panels 13, 13, are mounted within the frame in spaced relation. These panels are

spaced by means of marginal strips 14 which may be of felt, rubber or any other effective sealing and insulating material. The assembled glass panels and marginal separators 14 are slid as a unit through one side of the frame into the inner marginal grooves 15 of the frame, which grooves extend around three sides of the rectangular frame. The fourth side may be described as slotted as at 16, the slot being of the same width as the grooves around the inside 10 of the frame. Slot 16 is transversely grooved as at 17 to provide a slideway for retaining means hereinafter described.

5 A channel shaped strip 18 is slid into the groove 17 from the open end thereof, the other end of 15 the groove being closed as at 17a. The channeled side of the strip 18 faces outward and provides a slot when considered in relation to the wall of the groove 17 for receiving a spring steel strip 19. The first mentioned strip 18 is rigid and 20 functions to hold the glass panels in position. It includes a longitudinal centrally disposed slot 20, permitting insertion of an advertising or price card 21 into the space between the glass panels.

25 The spring steel strip 19 holds the price card 21 in position. This strip normally assumes a bowed condition, as shown in the perspective view, Figure 6. When it is slid into position the tendency to bow causes it to have a friction fit in the slot, tending to prevent accidental displacement.

30 A series of apertures 22 are provided along the length of the strip adjacent the slot 20. These apertures permit air circulation between the glass panels. They also afford means for 35 engagement by a sharp pointed instrument for sliding the strip out of position to a point where it can be grasped as shown in Figure 3.

35 Since the vent holes 22 are at the bottom of the sign, they do not permit entrance of rain or snow into the interior of the sign. By permitting equalization of temperature as between the environment of the sign and the interior thereof, there is no tendency toward frosting of 40 the glass and interference with the reading of 45 the matter on the card.

Having described my invention, I claim:

1. A sign for removably mounting a placard, said sign including an internally grooved frame, 50 said frame having a slotted side, a pair of glass panels insertable through said slotted side, packing or spaced strips interposed between said glass panels around the margins thereof, said assembled glass panels marginally supported within 55

- the groove of the frame, a slotted retaining strip inserted longitudinally of the slotted side of the frame for holding the glass panels in position but permitting insertion of the placard through
5 the slot thereof, and a removable strip insertable adjacent said last mentioned strip over said slot therein for holding a placard in position against removal from between said glass panels.
2. A placard holder, comprising, an internally
10 channeled frame, spaced glass panes mounted in the channel of said frame, a placard mounted between said panes, said frame having the channel at its lower side extended entirely therethrough and transversely grooved to provide a
15 longitudinal ledge, a slide having a central longitudinal slot, said slide insertable in the trans-

verse groove for retaining the panes in place, and a second slide inserted in the transverse groove over said slot for preventing displacement of the placard therethrough.

3. A supporting frame for removably mounting 5 a placard in vertical position, said frame including internal channels for receiving spaced glass panels, a placard disposed in the space between said glass panels, a removable supporting ledge disposed along the lower edge of the 10 frame providing a rest for the glass panels and the placard disposed therebetween and preventing downward displacement of the panels and placard.
